Howard M. Cohn(57) **CLAIM**

The ornamental design for an egg incubator as shown and described.

DESCRIPTION

FIG. 1 is a perspective view of a egg incubator showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of portion 9 in FIG. 1.

The broken lines depict portions of the egg incubator and form no part of the claimed design. The dash-dot broken lines in FIGS. 1 and 9 depict the boundaries of the FIG. 9 enlarged view and form no part of the claimed design.
